UNITED STATES PATENT OFFICE.

PHILIPP SEILER, OF CHICAGO, ILLINOIS, ASSIGNOR, BY MESNE ASSIGNMENTS, TO ALEXANDER M. V. SCHERMERHORN, SAMUEL S. BUTLER, AND LUKE I. WILSON, OF CHICAGO, ILLINOIS.

MATCH-BOX.

SPECIFICATION forming part of Letters Patent No. 714,749, dated December 2, 1902.

Application filed May 29, 1902. Serial No. 109,434. (No model.)

To all whom it may concern:

Be it known that I, PHILIPP SEILER, a citizen of the United States, and a resident of the city of Chicago, in the county of Cook and State of Illinois, have invented certain new and useful Improvements in Match-Boxes; and I do hereby declare that the following is a full, clear, and exact description of the same, reference being had to the accompanying drawings, and to the letters of reference marked thereon, which form a part of this specification.

This invention relates to improvements in boxes, and is shown more particularly embodied as a match-box, though obviously the same is adaptable for use as a cigar or cigarette case, card-case, stamp-holder, and for many other purposes.

The object of the invention is to provide a box or case which cannot open when in the pocket, but which is so constructed as to be readily opened with one hand when desired. The construction is cheap, strong, and durable, and the case presents an attractive appearance.

The invention consists in the matters hereinafter described, and more fully pointed out and defined in the appended claims.

In the drawings, Figure 1 is a perspective view showing the box closed. Fig. 2 is a similar perspective view showing the cover slid to its releasing position. Fig. 3 is also a perspective view showing the box open. Fig. 4 is an enlarged transverse section taken through the lock or latch with the box closed.

As shown in the drawings, said case and the cover therefor are constructed of stamped or pressed metal. The box comprises a bottom portion A, having integral side walls a a' and one end wall a², as shown in Fig. 3, and having one of its ends open.

B indicates the cover, hinged to the side wall a' and provided on its margins with integral flanges forming the end wall b, adapted to close the open end of the box, and a side wall b', adapted to close over the side wall a. The side or margin of the cover opposite the side wall b' is hinged to the margin of the side wall a', said hinge, as shown, being constructed by bending parts of the side walls a' and

of the margin of the cover over a pintle a³. Said parts forming the hinge are of such relative size and width as to permit the cover B to slide longitudinally of the box portion. In the flanged side wall a is provided a downwardly-opening notch, which is extended at its bottom toward the end wall a², providing a forwardly-directed tongue of metal a⁴, integral with the side wall, and which is notched on its under side to receive the inwardly-turned hook or catch b² on the lower margin of the flange b' of the cover. Within the box is provided a plate C, having downturned edges c c', which fit closely between the sides a a' of the box and afford means for securing the plate in position either by soldering, indenting, or otherwise. The width of the flanges c c' is sufficient to hold said plate flush with the upper edges of the side walls of the box. Near the hinge said plate c is slotted longitudinally, as shown in Figs. 3 and 4, providing a narrow tongue c², which is bent upwardly and forms a leaf-spring, which is pressed downwardly when the box is closed.

The operation is as follows: When the cover is closed down over the box, the hook b² enters the notch in the top of the side wall a, the inclined end of the tongue a⁴ acting to force the cover forwardly with respect to the box. When the cover is retracted toward the closed end of the box, slipping the hook b² into the notch in the under side of said tongue, at which point the ends of the box and cover coincide, as shown in Fig. 1, the spring pressing upwardly on the cover acts to retain said hook in said notch. Should it now be desirable to open the case, it may be held in one hand and downward and longitudinal pressure applied to the cover with the thumb. As shown, a boss b³ is provided centrally on the cover to receive the pressure of the thumb in opening the box, though obviously the same is not necessary for the successful operation of the device. Said pressure forces the cover downwardly against the spring c² and longitudinally of the box sufficiently to permit the hook b² to register with the upwardly-opening part of the notch in the side wall. If the pressure is now released, the spring c² acts to force the cover upwardly, 100

as shown in Fig. 3, exposing the contents of the box.

Obviously details of construction may be varied without departing from the principles 5 of my invention.

I claim as my invention—

1. A box, an upwardly-opening cover hinged thereon and slideable longitudinally of the box, a catch on one margin of the cover adapted 10 to be slid into engagement in a downwardly-opening notch in a tongue extending longitudinally of the box.

2. A box having one open end, a cover hinged thereto and slideable longitudinally 15 thereof and having a flanged end adapted to close said end of the box and a catch on said cover adapted to engage in a recess in one of the box sides when the cover is fully closed.

3. The combination with a box having one 20 open end, of a cover provided with an end flange adapted to close said end when the cover is closed, and hinged laterally of and slideable longitudinally with respect to the box and a catch on the cover opposite the hinge, 25 adapted to engage beneath an integral tongue on the box side and a cover-plate flush with the top of the box and a spring thereon adapted to throw the cover open when the catch is released.

4. The combination with a pressed-metal box having one open end, of a rigidly-secured plate secured therein flush with its top and extending for a part of its length, and a longitudinally-slideable cover hinged to the side of the box, a marginal flange on said cover 30 adapted to close the open end of the box when said cover is closed, a tongue integral with the box side opposite the hinge and provided with a notch on its under side adapted to receive and shaped to retain a catch carried on 35 the cover, and a spring within the box acting to force said cover to its open position when said hook is released.

5. A box having a cover hinged thereto and slideable longitudinally therewith, said cover 40 when in its closed position forming part of the end wall of the box and interfitting parts on the cover and box whereby in opening the box the cover is pressed downwardly and slid longitudinally of the box and a spring within 45 the box acting to throw said cover open.

In testimony whereof I have hereunto subscribed my name in the presence of two subscribing witnesses.

PHILIPP SEILER.
